COMBINATION BOOT, SOCK AND MITTEN DRYER

George A. Donaldson, Sr., R.D. 1, Box 188, Phoenix, N.Y.

Filed June 8, 1961, Ser. No. 65,513

Term of patent 7 years

(Cl. D49—1)

FIG. 1 is a view in perspective of a combination boot, sock and mitten dryer showing my new design.

FIG. 2 is a view in side elevation of the combination boot, sock and mitten dryer.

FIG. 3 is a view in top plan of the combination boot, sock and mitten dryer.

FIG. 4 is a view in end elevation of the combination boot, sock and mitten dryer.

The side and end not shown are the same as the side and end, respectively, shown.

I claim:

The ornamental design for a combination boot, sock and mitten dryer, as shown and described.
